Primary Examiner — Jack Reickel*Assistant Examiner* — Salamah Jordan(74) *Attorney, Agent, or Firm* — Bayramoglu Law Offices LLC(57) **CLAIM**

The ornamental design for a fitness handle, as shown and described.

DESCRIPTION

FIG. 1 is a top perspective view of a fitness handle showing my new design;

FIG. 2 is a left side view thereof, a right side view being a mirror image of the left side view;

FIG. 3 is a top view thereof;

FIG. 4 is a bottom view thereof;

FIG. 5 is a front view thereof;

FIG. 6 is a rear view thereof; and,

FIG. 7 is a bottom perspective view thereof.

The broken lines depict portions of the fitness handle in which the design is embodied that form no part of the claimed design.

1 Claim, 7 Drawing Sheets(56)
